UNITED STATES PATENT OFFICE.

WILLIAM F. TROAST, OF LANCASTER, PENNSYLVANIA, ASSIGNOR TO ISSACHAR P. REESE, OF LANCASTER, PENNSYLVANIA.

SLIDING-SHACKLE LOCK.

Application filed August 24, 1923. Serial No. 659,134.

To all whom it may concern:

Be it known that I, WILLIAM F. TROAST, a citizen of the United States, residing at Lancaster, in the county of Lancaster and State of Pennsylvania, have invented certain new and useful Improvements in Sliding-Shackle Locks, of which the following is a specification.

This invention relates to locks, and more particularly to sliding shackle locks for use on automobiles and other vehicles to prevent tires from being stolen.

The invention resides more specifically in a stop means for preventing the insertion 15 of the shackle in the wrong end or bottom of the lock block, body or casing, and further resides in the particular shape of the shackle whereby the same, in combination with the lock body or casing, firmly clamps 20 the lugs to be secured together and guards against rattling or other noise that otherwise might be caused by the shackle of the lock striking against the lugs during the travel of the automobile or vehicle over the 25 roadway.

In the accompanying drawings:

Figure 1 represents a vertical cross-sectional view through a portion of a spare tire rack of ordinary construction in common use on automobiles, illustrating the application of my improved lock, shown in side elevation, to the securing lugs by which a mounted tire or casing is fastened to the rear of a vehicle;

Figure 2, a detail perspective view of the shackle;

Figure 3, a side elevation of the shackle, broken away, and of the lock body or casing broken away to show the spring top for preventing insertion of the shackle from the bottom, and indicating in dotted lines one leg of the shackle being partially inserted from the bottom and abutting against and being stopped by, the spring stop;

Figure 4, a detail sectional view on the line 4-4 of Figure 3, with the plates of the body or lock block or casing in place; and

Figure 5, a view similar to Fig. 4 of a 50 modification.

Referring now in detail to the drawings, the lock block, casing or body, comprises two plates A and B preferably riveted together by means of rivets C preferably 55 integral with one of the plates. These plates

between them enclose the usual lock mechanism, not shown, with the usual barrel E, of this sliding shackle type of lock, and are so formed that when riveted together they will provide the usual two parallel 60 bores or passages from top to bottom to receive the respective arms of the shackle D, the arms of which are parallel, or substantially parallel, with each other up to a point near the loop end of the shackle, starting at 65 which point each arm is bent in a straight inclined line toward the other arm, as at 1, for an appreciable distance, and then the ends of these inclined portions 1 are connected to each other by an intermediate, 70 preferably arcuate, bar 2, the inclined portions 1 and the bar or rod 2 together forming a loop with flattened side portions.

The free end portions of the arms have their opposed faces provided with notches 75 as usual for engagement by the usual locking bolts of the usual locking mechanism.

The key-hole is located in the bottom of the barrel E and is accessible only from the bottom of the lock casing, that is, that part 80 of the lock casing or body farthest away from the bar or rod 2, and when so arranged it is manifest easy access can be had to the key-hole for insertion of the usual key K under all conditions to work the lock mechanism, but it has been found that many users are careless and will apply the lock body or casing to the ends of the shackle arms with the key-hole presented toward the bar or rod 2 and will then force said body or casing on said arms to such degree that it is im-

possible to get a key into the key-hole by reason of the interference of bar or rod 2, or of the parts held by the shackle D, and it is therefore important to provide an easy manner of preventing such misapplication of parts, and at the same time to avoid any special construction or cross-sectional form of the arms of the shackle or of the passages, it being important to have as few manufacturing operations as possible to speed up production and to keep down expense of manufacture.

With the above considerations in view I provide a yielding spring pressed stop, preferably in the form of a leaf spring 3, mounted so as to extend into one of the passages in the block, body or casing for one of the arms of the shackles and adapted to yield and be displaced from said passage by the 110

said arm of the shackle as the latter is inserted, from the top of the lock body or casing, in said passage, but having an abrupt edge or end located near the bottom of the casing or body below all of the lock bolts and adapted to be engaged by the end of the shackle arm should an attempt be made to insert the shackle into the bottom of the lock 40 or casing, and to effectually prevent such 10 misapplication of parts.

In the present embodiment in order to have the spring stop or yielding stop function as above described I secure leaf spring 3 by means of a rivet 4 passing through its upper 15 end portion and the wall of plate A, with its leaf portion inclined downwardly and away from the wall of plate A into the lower part of the opening for one of the arms of the shackle, thus, as the end of the arm of 20 the shackle, in its insertion from the top, strikes the spring 3 it will strike against the inclined inner surface thereof and force the spring 3 out of said passage, while if it be attempted to insert the shackle from the 25 bottom the end of one of the arms of the shackle will strike against the end edge of the spring 3 and will be completely blocked thereby against further insertion in the lock body or casing.

30 The letter F designates the skeleton rim forming part of, and supported by, the usual iron tire rack, not shown, with which most automobiles are provided for carrying spare tires. A demountable rim G adapted 35 to have mounted on it a pneumatic tire or spare casing, is loosely fitted over the rim F. A metal lug H, bolted or welded, or both, to the rim F is provided with a notch or recess in its upper end, a perforation intermediate its ends and a bolt hole near its 40 lower end, and an opposing removable lug I, of usual type, having its lower portion downwardly inclined away from lug H and provided with a perforation and bolt hole 45 registering with the perforation and bolt hole in lug H and preferably, also, having a registering recess in its upper end, is normally tensionally held by a bolt and nut J with its adjacent face of its inclined portion 50 in engagement with the demountable rim G, forcing the latter over on rim F and also spreading rim G radially, to secure the rims F and G together and prevent any relative movement between these rims.

55 The walls of the perforation and recess in the lug H have abrupt edges, as shown in Fig. 1.

To lock the removable lug I to the lug H to prevent unauthorized removal of the rim 60 G with the spare tire mounted thereon, the shackle D has one arm passed through the registering perforations with the other arm lying in the registering recesses in said lugs H and I, the lock body, block or casing is 65 then applied, as above described, to the free

end portions of the arms of shackle D and forced thereon until it is in engagement with the adjacent face of lug I with the opposed faces of inclined portions 1 in biting engagement with the edges of walls of the perforation and recess respectively in lug H, thus guarding against any play between the lock and said lugs and preventing any rattling or noise, which otherwise might be caused by the lock striking against said lugs or other parts were any play left between the lock parts and said lugs. 70

In the modification illustrated in Figure 5, instead of the separate rivet 4 for fastening the spring 3 to plate A, I have provided a rivet stud 4^a formed integrally with plate A and adapted to have its end spread down over and against the adjacent portion of the spring 3 after the latter has been applied to said stud 4^a. Otherwise the construction, 80 and operation is in all respects the same as in the form previously described. 85

Having thus described my invention, what I claim as new and desire to secure by Letters Patent is:

1. In a sliding shackle lock, the combination of a sliding shackle having a loop at one end and an arm, with a lock casing having a passageway through it to slidably receive an arm of said shackle and suitable mechanism having means adapted to extend into said passage to engage said arm to lock the same in said passage, and means extending in said passageway adapted to be engaged by said arm and forced out of the said passage thereby when the said arm is inserted from the top of the lock casing, and engaging the end of the arm and obstructing said passageway and preventing the insertion of said arm when an attempt is made to insert said arm from the reverse direction with respect to said lock casing. 95

2. In a sliding shackle lock, the combination of a sliding shackle having a loop at one end and an arm, with a lock casing having a passageway through it to slidably receive an arm of said shackle and suitable mechanism having means adapted to extend into said passageway to engage said arm to lock the same in said passageway, and resilient means extending in said passageway and adapted to be engaged by said arm and forced out of the passageway thereby when the said arm is inserted from the top of the lock casing, and engaging the end of the arm and obstructing said passageway and preventing the insertion of said arm when an attempt is made to insert said arm from the reverse direction with respect to said lock casing. 110

3. In a sliding shackle lock, the combination of a sliding shackle with a lock casing having a passageway through it to slidably receive an arm of said shackle and suitable mechanism having means adapted to extend 115

into said passageway to engage said arm to lock the same in said passageway, and a leaf spring secured in said casing and having a free portion extending inwardly and downwardly into said passageway and adapted to yield under the influence of said arm and move out of said passageway as said arm is forced downwardly in said passageway, but adapted to block with its free end any attempted insertion of the arm erroneously in the reverse direction.

4. In sliding shackle locks, a lock casing having the usual passageway for an arm of

the sliding shackle, and a yielding element mounted in said casing and adapted to extend into said passageway when the said arm is not inserted therein and having an abrupt edge presented toward the bottom of said casing and closely adjacent thereto to block the lower end of said passageway against the insertion of the said arm from the bottom of said casing.

In testimony whereof, I have signed my name to this specification at Lancaster, Pennsylvania, this 18th day of August, 1923.

WILLIAM F. TROAST.
